UNITED STATES PATENT OFFICE

121,523

DESIGN FOR A GLOBE FOR LIGHTING FIXTURES

William B. Petzold, Pittsfield, Mass., assignor to
General Electric Company, a corporation of
New York

Application May 8, 1940, Serial No. 92,229

Term of patent 14 years

To all whom it may concern:

Be it known that I, William B. Petzold, a citizen of the United States, residing at Pittsfield, in the county of Berkshire, State of Massachusetts, have invented a new, original, and ornamental Design for a Globe for Lighting Fixtures, of which the following is a specification, reference being had to the accompanying drawing, forming a part thereof.

In said drawing:

Figure 1 is an elevational side view of a globe for lighting fixtures embodying my new design.
Figure 2 is a bottom plan view of the globe.

I claim:

The ornamental design for a globe for lighting fixtures, as shown.

WILLIAM B. PETZOLD.
